UNITED STATES PATENT OFFICE.

MILES A. SEED, OF ST. LOUIS, MISSOURI, ASSIGNOR TO THE M. A. SEED DRY PLATE COMPANY, OF SAME PLACE.

DETECTIVE CAMERA.

SPECIFICATION forming part of Letters Patent No. 436,745, dated September 16, 1890.

Application filed May 3, 1889. Serial No. 309,474. (No model.)

To all whom it may concern:

Be it known that I, MILES A. SEED, of St. Louis, Missouri, have made a new and useful Improvement in Detective and other Photographic Cameras, of which the following is a full, clear, and exact description.

In the construction hitherto generally in use a continuous film is employed. In the use of the camera the film is unwound from one reel and wound upon another reel. The film remains intact, and all the pictures taken are united, and the entire film must be withdrawn as one piece from the camera.

To provide an improved apparatus by means of which the pictures may be more readily taken, by means of which they can be taken and withdrawn separately from the camera, and the work be inspected from time to time as it proceeds is mainly the aim of this improvement. Additional features are a shutter of peculiar construction and a lens adjustable to longer and shorter focuses, all substantially as is hereinafter described and claimed, aided by the annexed drawings, making part of this specification, in which—

Figure 1 is a view in perspective of a film and its frame. Fig. 2 is a view in perspective of the film by itself. Fig. 3 is a vertical longitudinal section on the line 3 3 of Fig. 7. Figs. 4 and 5 are details, being views illustrating the different positions of the film-holder discharger and being sections on the line 3 3 of Fig. 7. Fig. 6 is a vertical cross-section on the line 6 6 of Fig. 3. Fig. 7 is a plan of the camera. Fig. 8 is a horizontal section on the line 8 8 of Fig. 3. Figs. 9 and 10 are details, being sections on the line 3 3 of Fig. 7, and showing, respectively, the springs and the roller-stops at the upper forward end of the magazine. Fig. 11 is a side view of the diaphragm partly unfolded. Fig. 12 is a view in perspective of the projection-bearing arm used in controlling the adjustment of the shutter. The forward end of the arm is shown in section. Figs. 13, 14, 15, 16, and 17 are all sections on the same line—namely, vertical cross-sections on a line between the front end of the camera and the shutter, and respectively showing the movable parts in different positions; and Fig. 18, a horizontal section on the line 18 18 of Fig. 3.

The views are substantially upon the same scale, saving Figs. 1, 2, 11, and 12.

The same letters of reference denote the same parts.

My improved apparatus is primarily, though not solely, intended for use where each sensitized plate or film is contained in a protecting-holder.

A, Figs. 1 and 8, represents a film-holder which I have devised, and which I prefer to use in connection with the present apparatus. It is formed, preferably, out of a single piece of metal or other equivalent material. *a* is the face of the holder, and *a'*, *a²*, and *a³* are flanges at the sides and bottom of the holder, and formed by bending the edges of the piece, so as to form folds adapted to receive the edges of the film *B*, Fig. 2, and thereby hold the film while within the camera, and also during more or less of its manipulation. The side folds are open at the top, and the holder between the side folds suitably made to admit the film and enable it to be slipped downward into place in the holder, as shown in Fig. 1. The top edge *a⁴* of the holder is preferably hemmed, as shown. The film *B* is preferably a celluloid one.

The camera *C*, Figs. 3, 7, 8, 13, 14, 16, and 17, is mainly divided into four compartments—*D*, the magazine, which occupies the upper rear portion of the camera, extending from the rear end *c* of the camera forward to the discharger *E* and serving to contain the films prior to their use; the operating-chamber *F*, through which the light passes from the lens-tube *G* to the film being used, and through which the film and holder, after being exposed, drop, and which chamber extends from the position of the discharger forward to the rear end *g* of the lens-tube; the lens-chamber *H* at the upper forward part of the camera, and which contains the lens *g'*, lens-tube, and other parts immediately therewith connected, and hereinafter set forth, and the receiving-chamber *I* in the lower portion of the camera, into which the films drop from the operating-chamber, and whence they can be withdrawn as desired. All of these compartments are suitably constructed to exclude the light, saving what is admitted through the lens-tube upon the films as they are exposed.

The films to be used are placed in the magazine D, are arranged one behind another therein, with the forward film in the row presented to the operating-chamber, and so as to be exposed to light admitted through the lens-tube, and they are so held and managed in the magazine as to be moved successively forward to the operating-chamber as fast as the forward ones in the row are discharged downward into the receiving-chamber. To this end, as the most desirable method, the magazine has a sliding door d to provide for the introduction of the films (held, respectively, in their holders) into the magazine, and ways 5 d' d', Figs. 3 and 8, are provided for the support of the film-holders after they have been placed within the magazine, and upon which the film-holders are slid in the direction of 10 the operating-chamber.

20 d², Figs. 3 and 8, represents a follower which exerts an elastic pressure upon the row of film-holders, the pressure being produced by means of a spring d³, one end of which bears against the rear wall c of the magazine or any 15 suitable shoulder and the other end thereof against the follower. To admit the films into the magazine, the follower is pressed backward in the magazine until there is space for the films in the front of the follower. To facilitate 20 the adjustment of the follower in this respect, a cord d⁴ is attached to the follower and extended thence rearwardly and through the wall c, and its outer end d⁵ is wound upon a button d⁶, Figs. 3 and 8. By rotating the button 25 the cord is wound upon it, and the follower and spring thereby pressed backward in the magazine and held at the desired point therein. The films and their holders are then placed 30 in front of the follower and the cord released 35 from the button, whereupon the spring expands and causes the parts to assume the position shown in Figs. 3 and 8. The door d is now supposed to be closed, and the opening in the wall c being, in practice, sufficient only for 40 the passage of the cord d⁴, no light can enter 45 the magazine. The row of films and holders is thus pressed forward until the foremost film-holder at its lower end encounters the dis- 50 charger E and at its upper end presses against one or more springs d⁸, Fig. 3. The upper front corner of the film-holder also encounters stops, preferably in the form of frictional rollers d⁹, which are suitably journaled 55 in the roof of the camera or other fixture, so as to hold the film-holder back until it is to be discharged, and then to facilitate the discharge of the film-holder whenever its discharge is desired. The springs d⁸ are contrived to exert an elastic pressure downward 60 upon the foremost film-holder as it rests upon the discharger E. This last-named part in its most desirable form is substantially a shaft e, having two flanges e' and e² and means for rotating it forward and backward. It extends 65 across the camera, Figs. 3, 4, 5, and 6, and is journaled in the side walls c' c' thereof, and it is at a suitable level to receive the foremost film-

holder between its flanges e' e² when the shaft e is in the position shown substantially in Fig. 3. In this position the film-holder rests upon the flange e', and its front is against the flange e². The shaft e is provided with a crank e³, Figs. 3 and 8, by means of which the shaft can be rotated to discharge the film-holder and film, and at e⁴, Fig. 6, is shown a spring whose function it is to restore the shaft into the position of Fig. 3 whenever the crank e³ is released. 75

The operation of the camera as thus far described is as follows: Let the parts be arranged as in Fig. 3 and the foremost film be exposed to take a picture. After taking the picture the lens is covered in the usual manner to exclude the light from the operating-chamber. The film and its holder are then 80 as one part discharged from the magazine through the operating-chamber into the receiving-chamber I. To effect this, the dis- 85 charger E is operated by means of a cord e⁵, Fig. 3, leading downward through the bottom c² of the camera, substantially as shown, and so as to be conveniently reached, the operator is enabled to rotate the crank e³. This causes the shaft e to turn in its bearings and its flange e' to lift the film-holder, as indicated substantially in Fig. 4. The springs d⁸ yield as the film-holder is pressed upward against them. The film-holder continues to be thus upheld until the shaft e has been rotated sufficiently for the flange e² to be inclined downward and the flange e' to point toward the operating-chamber, substantially as indicated in Fig. 5. The film-holder at its lower end is now free, and it slips from off the discharger and drops toward the receiving-chamber. Its downward movement is hastened by reason of the action of the springs d⁸, which, after aiding in steadyng the film-holder during the taking of the picture, now serve to press it downward and to expedite 90 its descent. The rollers d⁹ rotate as the film-holder in its described movement is rubbed against them. Instead of allowing the holder to drop directly into the receiving-chamber, it is desirable for it to be dropped first onto 95 a flexible flap J, Figs. 3, 4, 5, and 8, which serves to cushion the film-holder as it falls to form a chute inclining downward toward the receiving-chamber to enable the film-holder to be delivered horizontally into the receiving-chamber and to form a valve, which, after 100 the film-holder shall have passed the flap, rises and closes the outlet f, Figs. 3 and 4, from the operating-chamber and prevents the admission of light through the outlet to the operating-chamber. In Fig. 3 the flap is in position to close the outlet f. In Fig. 4 the outlet is still closed. In Fig. 5 the outlet is opened and the flap is serving as a chute to direct 105 the descent of a film-holder into the receiving-chamber. The film-holders, containing their respective films, assume the form of a pile in the receiving-chamber, as indicated in Fig. 3. The receiving-chamber is provided 110

with a suitable door *i* to enable the film-holders and films to be withdrawn from the receiving-chamber, as desired. The rotation of the crank *e*³ and shaft *e* is limited by suitable stops *e*⁶ *e*⁷, Figs. 3, 4, and 5. As the discharger is rotated back again into the position of Fig. 3 its flange *e*' presses the film-holder next to it (and with that film-holder those in the rear thereof) far enough back in the magazine to enable the point of the flange to pass beneath the film-holder, whereupon the film-holder at its lower end slips forward above the flange *e*' and into the position of Fig. 3. To this end the flange *e*' is rounded at the back, substantially as shown. The film-holders and their films are thus successively used and shifted one by one from the magazine to the operating-chamber, and thence into the receiving-chamber until the magazine is exhausted, whereupon the magazine is refilled with film-holders and films and the operation repeated.

The device as thus far described may be operated with any ordinary lens and lens-tube. It is better, however, for the camera to be adaptable to focuses of longer or shorter lengths. To this end the lens-tube *G*, Figs. 3 and 8, carrying the lens *g*', is made adjustable forward and backward in the camera. This, in the present instance, is carried out by holding the lens-tube in a sleeve *g*², which, in turn, is secured to the partition *g*³, which forms the rear wall of the lens-chamber *H*. By means of the lever *g*⁴, pivoted at *g*⁵ to some fixture—such as the side of the camera—and having its free end *g*⁶ extending through a slot *g*⁷ in the opposite side of the camera and connected with a pin *g*⁸, which extends from the lever through a slot *g*⁹ in the sleeve to connect with the lens-tube, the lens-tube can, within certain suitable limits for the purpose named, be shifted longitudinally toward and from the operating-chamber. Any suitable means may be adopted by which the operator is enabled to know how far the lever end *g*⁶ shall be moved to adjust the lens to any predetermined focus. The lever is slotted at *g*¹⁰ to provide for the movement of the pin *g*⁸ in the lever as the lens-tube is adjusted. The lens-chamber has a lid *h* to provide access to the chamber.

K, Fig. 11, represents an adjustable diaphragm used in connection with the lens-tube and lens. It is a series of leaves *k*, each having a diaphragm-opening *k*', but the openings in the respective leaves being of different diameters. The leaves are pivoted together at *k*² to enable them to be handled as one piece. When a certain diaphragm is needed, the leaf *k* having that opening is inserted in the slit *k*³, Fig. 3, in the lens-tube, so as to bring the opening *k*' into coincidence with the lens, and the diaphragm is changed by withdrawing the leaf that is in the slit and inserting another leaf having the desired opening. Those of the leaves *k* for the time being not in use in the lens-tube constitute a handle, by which the leaf in use is manipu-

lated. The leaves can be folded into a compact form.

The camera is rendered more complete by the embodiment therein of a shutter *L* of peculiar construction, for an understanding of which reference is made to Figs. 3, 8, 12, 13, 14, 15, 16, 17, and 18. The shutter is arranged between the forward end of the lens-tube and the forward end of the camera. It is mainly a circular plate having openings *l*, through which the light is admitted to the lens-tube, and intermediate imperforate portions *l*', which shut out the light. The plate is hung upon a shaft *l*², which is journaled in bearings *l*³. When the plate is rotated, its openings *l* and portions *l*' are successively moved past the lens-opening *g*¹¹ in the front wall of the camera and between it and the lens-tube. Its motion is produced by means of a coil-spring *l*⁴, Fig. 3, one end of which is fastened to the shaft *l*² and the other end to the plate or to some part, such as the case *l*⁵, attached to the plate. The shaft is provided with a knob *l*⁶, by means of which the shaft can be rotated in its bearings and the spring *l*⁴ thereby wound, during which operation the plate is held stationary. The shaft is provided with a ratchet *l*⁷, which coacts with a fixed pawl *l*⁸, to prevent the shaft *l*² from turning backward when the knob is released. The spring being wound and the shaft prevented from turning backward, as described, the spring acts to effect the rotation of the plate whenever that part is released. To enable the rotation to be effected so as to produce either a flash or a time exposure, as may be wished, the following means are preferably adopted: The plate *L* is provided with two sets of laterally-extended projections, one set being designed for use in producing both flash and time exposures, and the other set in producing time exposures. These projections may be in the form of pins. *M M'* represent one set of the pins—say those used in both flash and time exposures—and *N N'* represent the set of pins used in time exposures. The pins *M M'* are set a certain radial distance from the center of the plate, and when the plate rotates the orbit of the pins *M M'* may be represented by the broken line *m*. The pins *N N'* are set a certain shorter radial distance from the center of the plate, and their orbit may be represented by the broken line *n*. The pins *M M'* and the pins *N N'* are upon different radial lines. The pins *M M'* are designed to co-operate with a stop or a system of stops to the end that the plate may be held at rest in a position in which an imperforate portion of the plate shall exclude the light from the lens-tube, then released and allowed to rotate to carry an opening *l* past the lens-opening *g*¹¹ and lens-tube, and thereby momentarily admit light to the lens-tube and then be arrested again in its rotation when an imperforate portion *l*' of the plate is in position to exclude the light.

The pins *N N'* are designed to co-operate

with a stop or a system of stops, whereby the plate can be released and allowed to rotate until one of its openings l is brought into coincidence with the lens-opening and lens-tube, and then be arrested in its rotation for an indefinite period of time to suit the purposes of the operator in obtaining a time exposure. To these ends the sets $M M'$ and $N N'$ may each be composed of a suitable number of pins, and the pins $M M' N N'$ may be suitably relatively arranged upon the plate, and also suitably arranged with reference to the openings l and portions l' , and the shutter may have any suitable number of openings l and portions l' , and the stops or systems of stops referred to may be correspondingly and suitably relatively constructed and arranged; but what I consider the best way is the one exhibited in the drawings. The pins $M M'$ are respectively arranged opposite the imperforate portions l' , and the pins $N N'$, respectively, opposite the openings l . Two openings l and two imperforate portions l' are shown; and the stop or escapement device is as follows: O , Figs. 3, 12, 13, 14, 15, 16, and 17, is an arm, which at its end o is pivoted to a fixed bearing o' , and whose other end o^2 is free to be moved upward and downward sufficiently to effect its purpose. At its end o^2 the arm is extended upward at o^3 , and the extension in turn is provided with four lateral projections $P P'$ and $Q Q'$, substantially as is represented in Fig. 12. The projections $P P'$ project into the orbit of the pins $M M'$ or into the orbit of the pins $N N'$, according to the adjustment of the arm O , as presently described. The projection P' is spaced laterally from the projection P sufficiently for a pin $M M'$ to pass between them, and it is also spaced vertically sufficiently below the level of the projection P for a pin to pass above it, substantially as shown. The projections $Q Q'$ are respectively spaced beneath the projections $P P'$, substantially as shown. By means of the push-pin R , Figs. 13, 14, 15, 16, and 17, the free end of the arm O can be raised, and by means of the spring S the free end of the arm O is depressed whenever it is released. Suppose a flash exposure is desired. Assume the parts to be as represented in Fig. 16. The pin M is against the projection P , and the plate, by reason of the action of the coil-spring above described, tends to rotate on the shaft l in the direction indicated by the arrow X , Figs. 16 and 17. By means of the push-pin R the arm O can be and is raised from the position of Fig. 16 into that of Fig. 17. This causes the projection P' to be removed from in front of the pin M , whereupon the shutter rotates half-around, or until the pin M' is brought into the position previously occupied by the pin M . Now if the push-pin continues to be raised the pin M' encounters the projection P' , as shown in Fig. 17, and the rotation of the shutter is arrested. If the push-pin and the arm O , by reason of its weight or the action of the spring S or other cause, have dropped into their original positions, the pin M' then en-

counters the projection P . In either event the shutter is held substantially in the position of Fig. 17, with an imperforate portion thereof in position to exclude the light from the lens-tube. For another flash exposure the push-pin (which between exposures is allowed to drop) is again raised, and the projection P is again dislodged, and so on, arresting the rotation of the shutter always, so as to exclude the light from the lens-tube. For a time exposure the free end o^2 for the time being is permanently upheld, so as to bring the projections $P P'$ into the orbit of the pins $N N'$. For this purpose a wedge T , Figs. 3, 13, 14, 15, 16, 17, and 18, is used. By means of the bell-crank lever t , Fig. 18, or other suitable means, this wedge is adapted to be withdrawn from beneath the arm end o^2 , Figs. 16 and 17, or to be wedged beneath the arm end o^2 Figs. 13 and 14. When the arm end o^2 is thus wedged up and the push-pin is depressed, as in Figs. 13 and 14, the projection P is in the orbit of the pins $N N'$, and the shutter is held with one of its openings l in line with the lens-opening and lens-tube, and the light is admitted. If the push-pin is raised, as in Fig. 15, the projection P' is brought into the orbit of the pins $N N'$ and serves to arrest the rotation of the shutter. In this manner the exposure can be prolonged to any extent. When it is desired to terminate a time exposure, the push-pin is operated to enable the pin N or N' to be worked past the projections $P P'$, whereupon the shutter rotates again. The shutter would now be carried around so as to cause another of its openings l to come opposite the lens-opening but for the projections Q and Q' , one of which, according to the position of the push-pin, being in the orbit of the pins $M M'$, and thereby causing the arrest of the rotation of the shutter in its position shown in Fig. 13—that is, with an imperforate portion l opposite the lens-opening. By operating the push-pin again the pin M or M' is released and another time-exposure position of the shutter obtained. By withdrawing the wedge from beneath the arm end o^2 the parts are readjusted for flash exposures. But one-half of the arm O is shown in Fig. 12. In practice it is better to make this part double, as shown in Fig. 3—that is, the arm is forked and receives the shutter between its forks, and each fork has an extension o^3 , having the projections $P P' Q Q'$, and the pins $M M' N N'$ project from both sides of the shutter.

The openings $l l$ and the imperforated portions $l' l'$ in the shutter may, respectively, be of any suitable extent and shape.

The chamber U , Fig. 3, may be utilized as a closet. Its door is shown at u .

I claim—

1. In a photographic camera, the combination of a magazine, a rotary discharger at the lower part of the front of said magazine, provided with a supporting-shoulder for the film-holders and an upstanding shoulder to rest

against the face of the adjacent film, and a yielding stop at the upper part of the front of the magazine vertically above the discharger, substantially as specified.

5 2. A photograph-camera having the magazine, the discharger, the springs d^8 , and the rollers d^9 , substantially as described.

3. A photograph-camera having the magazine, the follower, the discharger, the springs d^8 , and the rollers d^9 , substantially as described.

4. The combination of the magazine, the follower, the spring d^3 , the cord d^4 , and the button d^6 , substantially as described.

15 5. The camera having the magazine, the operating-chamber, the receiving-chamber, and the flap J, substantially as described.

6. In a photographic camera, the combina-

tion of the magazine, the operating-chamber immediately in front of the magazine, the receiving-chamber adjoining and vertically below the magazine, the rotary discharger at the meeting point of the said three chambers, and the curved spring plate or chute projecting out of the operating-chamber below the discharger into the receiving-chamber, substantially as specified.

7. The combination, in the herein-described camera, of the discharger, the discharger-crank, and the stops e^6 e^7 , substantially as described.

Witness my hand this 26th April, 1889.

MILES A. SEED.
